(57) **CLAIM**

The ornamental design for the chair, as shown and described.

DESCRIPTION

This application is related to commonly assigned, concurrently filed applications Ser. No. 29/388,609 and Ser. No. 29/388,610.

FIG. 1 is an isometric view of the chair of the present design; FIG. 2 is a front elevation view thereof; FIG. 3 is a right side elevation view thereof, the left side elevation view being a mirror image thereof; FIG. 4 is a rear elevation view thereof; and, FIG. 5 is a top plan view thereof.

The broken lines in the figures are for illustrative purposes only and form no part of the claimed invention.
